Patented Mar. 2, 1915.

UNITED STATES PATENT OFFICE.

EMANUEL W. BORTMAN, OF NORRISTOWN, PENNSYLVANIA, ASSIGNEE TO WILDEMAN
MFG. CO., A CORPORATION OF PENNSYLVANIA.

CLOTH-CUTTING MACHINE.

1,130,369.

Specification of Letters Patent. Patented Mar. 2, 1915.

Application filed November 25, 1913. Serial No. 302,862.

To all whom it may concern:

Be it known that I, EMANUEL W. BORTMAN, citizen of the United States, residing at Norristown, Pennsylvania, have invented 5 certain new and useful Improvements in Cloth-Cutting Machines, of which the following is a specification.

My invention relates to that class of cloth-cutting machines designed for use in 10 cutting a pile of cloth upon a table in which a knife is operated by means of a motor supported with the knife, a knife-guard and a sharpener upon a suitable standard rising from a foot-plate adapted to slide over the 15 surface of the table under the cloth. In machines of this class, it has been necessary, heretofore, to detach or throw the knife-guard out of adjustment before the sharpener could be brought in contact with the 20 blade and as the blade has to be sharpened every few minutes, this is a serious objection.

One object of my invention is to overcome this difficulty which I do by my arrangement and construction of parts as herein set 25 forth whereby the knife guard can be easily raised out of the way to permit the sharpener to operate upon the blade or to allow the blade to be readily detached from the 30 machine, without changing the adjustment or set of the guard in any way.

Other objects will hereinafter appear.

In the accompanying drawings: Figure 1 is a side elevation showing the guard device and the sharpener in their normal positions, 35 Fig. 2 is a similar view showing the sharpener in contact with the blade and the guard device in its raised position, Fig. 3 is a front elevation and illustrates how the blade can 40 be easily detached from the machine when the guard device is in its raised position, and Fig. 4 is a plan view of the knife guard device.

Referring to the drawings, 1 indicates a 45 rotary blade or knife detachably mounted upon a standard 2, having a base 3, and carrying an electric motor 4, for actuating said blade. A rearwardly extending handle 5, is provided for guiding and propelling 50 the machine. The sharpener 6, is of any approved design and is held normally out

of engagement with the blade as shown in Fig. 1.

The knife guard device consists of a curved bar 7, adjustably secured to a bracket 8, by means of a clamp screw 9 passing through a slot 10 in the bar and through an opening in the bracket, a thumb nut holding the clamp and screw in place. On the bracket is a lug or projection 11 in which is secured the front end of a rod 12, slidably pivoted in bosses 13 and 14 depending from a plate 15 attached to the base of the motor. At the other end of the rod 12 is a finger piece 16 which is so positioned near the handle 5 that it may be operated by a slight movement of the right thumb without the hand leaving the handle of the machine. The guard bar 7 is adjustable circumferentially of the blade so that its presser-foot 17 can always bear on the cloth to be cut, whether there is one thickness or many, and serve as a guide for the knife to follow. A collar 18 is secured to the boss 13 which serves as a bearing for one end of a spring 19 that encircles the rod 12, while the other end of this spring is fastened in a clutch member 20 carried by the rod 12. The boss 14 carries a clutch member 21 arranged to engage with the clutch member 20, said clutch members forming a lock for the guard to hold it in guard position. This lock is automatically set by the spring 19 which also serves to automatically swing the guard laterally and upwardly when the lock is released. The motor base carries a resilient stop 22 against which the projection 11 on the bracket 8 will bear when the guard device is in its raised position.

In operation, the guard device is over the 55 blade as shown in Fig. 1, where it protects the hand of the operator in holding the cloth to be cut in front of the knife, and the presser-foot has been adjusted to bear on the cloth and acts as a guide as stated above. Now, if it is desired to use the sharpener on the blade, the finger piece 16 is pushed forward by the operator's thumb which will disengage the clutch members 20 and 21 and allow the spring 19 to turn the 1 guard device upwardly and outwardly from the blade until its movement is limited by

the stop 22 which will constitute the raised position of the device as shown in Figs. 2 and 3—approximately at right angles to its normal position. The sharpener may then 5 be brought into operation or the blade may be removed from the machine as desired. To return the guard device to cover the edge of the blade, it is only necessary to bear down on the finger piece 16 against the 10 pressure of the spring 19 until the clutch members 20 and 21 are in alinement when the spring 19 will act longitudinally of the rod and cause the clutch members to snap into engagement. This pressure of the 15 spring will keep the clutch members locked, thereby securely holding the guard in place over the cutting edge of the blade.

It will be observed that the adjustment or 20 set of the guard is not disturbed in that it is not adjusted about the circumference of the knife in order to clear the edge for 25 sharpening. This would require care and attention on the part of the operator in readjusting the guard. With my arrangement, the adjustment of the guard is not altered in order to clean the knife, it not 30 being necessary to disturb the adjusting screw or alter the relation of the guard with its presser-foot to the goods being operated upon. Nor is the relation between the guard 35 and its supporting bracket changed in exposing the knife for sharpening. The whole bracket is swung aside with the guard maintained in proper adjustment thereon so that it is only necessary to swing the bracket back into place whereupon the proper relation of the guard to the knife will be assured.

The spring performs the two-fold function of moving the guard laterally and upwardly in respect to the knife and of effecting 40 its locking automatically when returned to working position. It is important that locking of the guard in position be assured with the least attention on the part of the 45 operator to insure safety and render carelessness on the part of the operator negligible. With the arrangement shown, the operator need only exert the proper pressure and turn the guard back to the knife 50 and the mere release of longitudinal pressure will cause the locking to follow.

What I claim is:

1. In combination in a cloth cutting machine, a cutter, a guard therefor movable to and from guard position in relation to the cutter, and an automatic spring lock for holding the guard in guarding position, substantially as described.

2. In combination in a cloth cutting machine, a cutter, a guard movable laterally and upwardly in relation to the cutter and a spring lock for holding the said guard in guard position, substantially as described.

3. In combination in a cloth cutting ma-

chine, a cutter, a guard therefor movable 65 automatically, when released, away from the cutter to expose the same, and a lock for holding the guard in guard position, substantially as described.

4. In combination in a cloth cutting machine, a frame with a rear handle, a cutter mounted thereon, a guard for the cutter turnable about an axis parallel with the side of the cutter, a spring for turning the guard away from the cutter when released, and a 75 lock for holding the guard in guard position, the said spring exerting force axially to hold the lock set, substantially as described.

5. In combination, a frame, a cutter mounted thereon, a guard having movement laterally and upwardly in respect to the cutter and about an axis parallel with the side of the cutter, a lock for holding the guard in guard position and comprising a member 85 shiftable in line with the axis of the guard to release and lock the same, and a spring for operating the guard when released.

6. In combination a frame, a cutter mounted thereon, a guard having movement laterally and upwardly in respect to the cutter and about an axis parallel with the side of the cutter, a lock for holding the guard in guard position and comprising a member shiftable in line with the axis of the guard 95 to release and lock the same and a spring for operating the guard when released, said spring acting to hold the lock set, substantially as described.

7. In combination a frame, a cutter mounted thereon, a guard mounted on the frame and turnable about an axis substantially parallel with the side of the cutter, a rod connected to the guard and extending coincident with the axis thereof, a lock for holding said rod against turning and releasing said rod when moved longitudinally, spring means controlling the rotation of said rod and its locking movement, and a finger piece for operating the rod, substantially as described.

8. In combination in a cloth cutting machine, a frame with a rear handle, a cutter mounted on the frame, a guard therefor turnable about an axis parallel with the side 115 of the cutter, a spring for swinging the guard away from the cutter when released, a lock for holding the guard in position adjacent to the cutter, and a rod connected with the guard, extending to a position adjacent to the handle and movable longitudinally to release the lock and set the guard free, substantially as described.

9. In combination in a cloth cutting machine, a cutter, a guard movable laterally and upwardly from the cutter, a lock comprising clutch members to maintain said guard locked in position over the cutting

edge of said cutter, a spring member to maintain said clutch members locked when in engagement and to maintain said guard in a raised position when said clutch members are out of engagement, and means for supporting said guard, substantially as described.

In testimony whereof, I affix my signature in presence of two witnesses.

EMANUEL W. BORTMAN.
